TRANSMISSION

Clarence W. Hansell, Port Jefferson, N. Y., assignor to Radio Corporation of America, a corporation of Delaware

Application June 5, 1936, Serial No. 83,643

7 Claims. (Cl. 178—7.1)

This invention concerns transmission methods and systems in general and in particular transmission systems wherein a broad band of signal frequency is to be put on a carrier frequency for signalling purposes. The present invention is particularly applicable to methods of and means for facsimile, television and similar types of signalling.

In describing my invention reference will be made to the use of the same in facsimile work although I contemplate the use of my method and means in all known types of signalling systems, including television in particular, since television is little more than a high speed facsimile transmission system in which no attempt is made to produce a permanent record of the received pictures.

One of the defects present in known picture and facsimile transmission systems is the loss of definition occurring in the transmitter circuits, during transmission, and in the receiver circuits or due to the same and to poor definition of the message being scanned, which becomes apparent in the reproduced message. In facsimile transmission of typewritten material this may show up due to blurred letters or parts of letters or change in density of background which is accentuated by imperfect transmission and which causes loss of definition and intelligibility in the received message. An object of the present invention is to provide a facsimile or television transmission circuit including novel means for correcting this loss of definition inherent in present systems and for increasing or exaggerating the definition present in the original message so that the reproduced copy may be equal to or even more intelligible than the original. Other objects will become apparent from the description of the method and means for accomplishing the main object.

In one form of my invention I supplement the direct current potential changes, or variations in current intensity, produced by scanning the message, by additional derived potentials which may vary substantially in proportion to the rate of change of light produced by scanning the message. Both variations are then caused to energize amplifying or relaying means and good definition of the message is insured more nearly irrespective of the condition of the original message or loss of definition in the transmission circuits and medium. The potentials I produce, which vary substantially in proportion to the rate of change of light produced by scanning, can be made to increase the percentage variation

in potential or current relative to the percentage variation in the light produced by scanning. In other words, the changes or rate of changes in light intensity, as compared to the average or total intensity, are made to have a greater or exaggerated effect upon the scanner output current. In this manner loss of definition due to any cause is reduced.

In some cases entire control is desirable by means responsive to the rate of change in light caused by scanning. For example, rate of change control is particularly applicable to typewritten and similar material where the periods of scanning black are short compared with the periods of scanning white. Rate of change control completely eliminates the problem of adjustment for background in the transmission of plain messages. In handling commercial messages the direct current control may be cut in only when the message has large black areas too wide to be handled by the rate of change control.

In describing my invention reference will be made to the attached drawings throughout which insofar as possible, like characters indicate like parts and in which,

Figures 1 and 1a illustrate a transmission system by means of which a wide band of signal currents or potentials of possibly poor definition are caused to produce a corresponding band of currents or potentials modified in such a manner that they represent corresponding signals of good definition and means for placing the same on a carrier wave for transmission purposes;

Figures 1b, 2, 3, and 4 show modifications of the arrangement of Figure 1. In each of Figures 2, 3, and 4 I have shown different circuit arrangements for producing the controlling currents or potentials which are partially or fully responsive more or less in proportion to the rate of change of light produced by scanning and means energized by said currents or potentials alone or by the same with currents the intensity of which are characteristic of the signals for controlling wave energy; while

Figure 5 is a curve illustrating the characteristics of the rate of change potential producing circuits.

Referring to Figures 1 and 1a of the drawings, the message to be scanned may be carried by a drum 10 cooperating with a source of light 12 and a lens system 14, 16, and diaphragm 18 to produce a ray of light falling on the input electrode 20 of a tube 24 the output electrode 26 of which is connected by way of a resistance 28 to a source of potential shown for convenience as 30

a potentiometer resistance PR. The potential variations produced across 28 are applied to the screen grid electrode 30 of an electron discharge device 32 the anode of which is connected with the plate circuit of a full wave modulator 40. The full wave modulator 40 has its input electrodes coupled by transformer 42 to a source of carrier wave energy.

Full wave modulator 40 has its anode electrodes coupled by transformer 46 to an output circuit which may lead to any utilization point directly or by way of filters which remove undesired output frequencies. Condensers Cn serve to neutralize the coupling which would otherwise exist between control electrodes and anodes of the tubes in modulator 40 so that the output current can be modulated substantially down to zero. If screen grid tubes are used in the modulator the neutralizing condensers may be omitted.

The tube 24 is a multi-stage electron multiplier amplifier constituted by a plurality of pairs of opposed plates axially disposed in an evacuated container with their faces lying in parallel planes as shown in Figures 1 and 1a. For convenience the upper electrodes or plates have been designated in the art by the term "upper" or "accelerating electrodes" and the lower plates have been designated by the term "lower" or "multiplying electrodes." Preferably the faces of the multiplying electrodes are specially prepared to enhance their ability to emit secondary electrons when they are struck by electrons arriving from other electrodes. Variations in light intensity falling upon electrode 20 causes variations in the number of electrons emitted from it. These electrons under the influence of electric and magnetic fields present in the tube are caused to strike the next adjacent secondary emission electrode, producing secondary electrons the number of which is multiplied in the tube. The electron device 24, when so energized, produces a greatly amplified output in the circuit 26, 28. An electro-magnetic means in the form of winding 23, on a magnet 21, energized through variable resistance 25 by a source 28, is provided for the purpose of causing the electrons emitted from 20 under the action of the light ray and from the succeeding lower plates to describe approximately trochoidal paths from each lower electrode to the next adjacent lower electrode, thus permitting the use of high accelerating potentials on the upper electrodes.

The secondary emission produced by electrons striking the plates increases the current arriving at successive electrodes until finally the current arriving at anode 26 may be several million times the photo current from electrode 20, if the tube has a sufficient number of stages.

This brief description of this electron multiplying tube is sufficient for the purposes of the present invention. For those interested, a fuller description of said tube may be found in United States patent to V. K. Zworykin, # 2,078,304, issued on April 27, 1937.

As pointed out briefly above, the screen grid 30 of tube 32 is energized by the amplifier potentials in the output circuit 26 to control the amplifier 32 which in turn modulates the modulator 40. The screen grid potential is made to vary in response to the total light falling on the electrode 20. By means of this control the light when varied from maximum to minimum value may make the audio output from the modulated tubes 40 change from zero to maximum.

In my novel method and means I also produce rate of change control potential and impress the same on the control grid 31 of tube 32. This additional potential may be produced by variable resistor R and variable capacity C connected as shown between a point on 28 and the control grid of tube 32. This resistive-reactive coupling R, C causes the control grid potential to vary more or less in proportion to the rate of change of screen grid potential. As a result, the natural loss of definition due to variable reflecting power of the paper, variable color of paper, poor typing, size of the scanning spot, etc., is reduced. If the response to the rate of change of light falling on the photocell is made great enough all variations in the light produce a still greater percentage of variation in the output from the modulator tubes.

This increase in percentage response tends to overcome the unavoidable loss of definition in scanning the subject. The response to rate of change of control grid potential may be controlled by adjusting the resistance R and the reactance C. Normally the response of R, C increases with increase in frequency, or rate of change of the current, in 28 up to rates of change at which the reactance of C is a negligible factor in the circuit. A more flexible control of the rate of change potentials may be had by supplementing the action of R, C by a capacity C₁ shunting the resistance 33 as shown in Figure 1b. If the values of R, C and C₁ are properly adjusted the amplitudes of the rate of change potentials supplied by R, C to the controlling electrode grows as the frequency of the initiating current increases until a preselected upper value is reached at which frequencies the condenser C₁ of Figure 1b shunts the potentials so that they are of decreasing value above this frequency. The characteristic of the circuit R, C, 33 and of the circuit R, C, C₁, 33 of Figure 1b, taken in combination with the other circuit elements, has been illustrated in Figure 5. These response characteristics of Figure 5 will, of course, be further modified, by limitation in rate of change determined by the size of the scanning spot, by filters and other elements associated with the system.

In general R and C and C₁ are so adjusted that the rate of change potentials produced by variations in current intensity are proportional to the value of the desired frequencies, and the desired frequencies are determined by taking into account not only those frequencies required to reproduce the message accurately but also those frequencies which may be permitted on the circuit without interfering with other channels or circuits.

In practice R and C or R and C and C₁ are adjusted to produce optimum permissible signal definition. The other electrodes of the tube are energized as shown and a description of the energizing circuits for these electrodes is thought to be unnecessary.

Biassing potentials for the control grid of 32 are supplied through resistance 33 connected as shown to any source of potentials. Any alternating current appearing in resistance 33 may be shunted out of the power source by a condenser 34.

For scanning typewritten material or other subjects where the periods of scanning black are short compared with the periods of scanning white, or vice versa, it is possible to employ nothing but rate of change response, thus eliminat-

ing the direct current element of control altogether. This eliminates the problem of adjustment for background and transmission of plain messages. The direct current control may be 5 cut in only when the object has large black areas too wide to be handled by the rate of change control. The switching means S in Figure 1 permits the use of the reactive circuit RC along or 10 supplemented by the direct current control on 30.

There are, of course, a great number of detail 15 circuits by means of which rate of change modulation or keying may be applied to an electrode in the amplifier tube 32. In general, they all involve a capacity or a transformer coupling of 20 some kind for transferring alternating potentials or current. When the alternating current component of coupling is made large in comparison with a parallel direct current coupling, or when 25 the alternating current component is greater than the threshold and limiting values passed on by a succeeding limiter amplifier not shown in the drawings, then an increase in definition or an exaggeration of variations in input current is obtained.

In Figure 2 I have shown a transformer means 30 for stepping up the rate of change potentials and applying the rate of change modulating potentials to the control grid 31. The rate of change modulating potentials supplement or replace, according to the position of switch S, the modulating current potential applied to the screen electrode 30.

In Figure 3 the thermionic tube 32 is shown 35 as a triode having electrodes including a control grid 31 and the direct current potentials characteristic of light intensity as well as the potentials which vary in accordance with rate of change of light are applied to the control electrode 31 by 40 way of an auto-transformer 52. The primary of this transformer is connected with the output impedance 28 as shown by way of a condenser C₄ large enough to pass the alternating current component of the output of 24. The alternating 45 current component potentials are stepped up and appear in the secondary of 52 from which they are supplied to the grid of 32. Figures 2 and 3 are in other respects sufficiently similar to the circuit of Figure 1 to eliminate the necessity of 50 describing these figures in detail.

In the modification of Figure 4 the rate of change modulating potentials are supplied by way of a variable reactive element 60 from the high potential end of resistor 28 which also supplies 55 the currents the intensity of which are characteristic of light intensity directly to the screen electrodes of the modulator tubes in 40 which are in this embodiment of the screen grid type. Movement of the point 64 on 28' permits the 60 direct current to be regulated from minimum to maximum, while adjustment of the value of 60 permits the rate of change potentials to be regulated from minimum to maximum. These adjustable controls permit control of the modulator by either or both the currents of varying 65 intensity or the potentials which are of amplitude commensurate with the rate of change of the intensity of the varying currents.

The carrier wave potentials are supplied to the 70 control grids of the tubes of modulator 40 as in Figures 1, 2, 3, while the modulated wave energy is taken from the anodes as in the prior figures.

Employment of rate of change control at the transmitter is of course, chiefly effective in 75 reducing loss of definition in the transmitter end.

If there is further loss of definition in transmission, including that due to filters, tuned circuits, etc., then similar circuits may be used at the receiver for increasing the definition again. Also, if desired, all increase of definition may be made 5 at the receiver, though this may involve some loss in effective signal-noise ratio.

It may be noted that rate of change tends to give the same result as would be obtained if the length of spot covered by the transmitter scanner 10 were reduced and this combined with limiting at top and bottom of the signal character can make the system more independent of density of the marks on the paper and of the density of the background formed by the paper. This enhancement of definition may be carried to a point to which manual adjustment of the scanning and transmitting apparatus by the operators when changing messages having widely different background density and color and widely varying 15 marking density and color will be dispensed with.

Although I have shown a tube of the electron multiplier type for converting the scanned light into current it will be understood that the tube shown is merely illustrative and may be replaced 20 by any appropriate tube known in the art, or by a selenium cell or equivalent element cooperating with a discharge device in a circuit of appropriate design to convert the scanned message into 25 controlling currents and potentials.

I have illustrated my invention with figures 30 most appropriate to facsimile transmission in which the object to be scanned is moved to accomplish the scanning but it will be obvious to anyone skilled in the art that my invention applies equally well to television scanning by moving 35 electron beams as described by Zworykin and Farnsworth. Application of my invention to both transmission and reception of television images 40 will result in marked improvement in definition, particularly at the higher modulating frequencies.

Although I have shown simple resistance and 45 capacity elements for carrying out my invention it will be understood that I may use more complex arrangements of resistances, capacities, inductances, amplifiers, etc., in order to obtain varying increase and decrease of response for various values of rate of change or equivalent modulating frequencies. I may, for example, shunt 50 the capacity C of Figure 1 with a resistance so that the relative output modulation from modulator 40 holds fairly constant up to certain modulating frequencies and then increases for higher frequencies.

It may also be noted that my invention is applicable to photocell-amplifiers such as are used 55 in sound moving pictures in reproducing sound from film.

I claim:

1. In a system for enhancing the definition of 60 indicia reproduced by facsimile comprising means for scanning the indicia, means for producing current variations characteristic of the light values thereof, means for producing potential variations characteristic of the rate of 65 change of the aforesaid current variations, an electron tube having an output electrode, and means for independently varying the impedance of the tube in accordance with the produced current and potential variations.

2. In a system for producing controlling potentials characteristic of a wide band of signalling current comprising an indicia-bearing surface, a source of light the intensity of which varies in accordance with the light values of said 75

surface, an electron discharge device controlled in accordance with said variations in light intensity, said electron discharge device having its output electrode connected in an output circuit 5 including an impedance, an additional electron discharge device having a first and a second control electrode and an output electrode, a utilizing circuit connected to said output electrode, a direct current circuit connecting the output electrode 10 of said first named discharge device to said first control electrode, and a reactive circuit including a series resistance and condenser connecting the output electrode of said first-named device to said second control electrode, whereby 15 said second control electrode will be subjected to voltage variations corresponding to the rate of change of the voltage variations impressed on said first control electrode.

3. In a system for signalling, a source of light 20 the intensity of which varies in accordance with indicia marking on a tape, an electron discharge device controlled in accordance with said variations in light intensity, said electron discharge device having its output electrode connected in 25 an output circuit including an impedance, a second electron discharge device having a plurality of control electrodes and an output electrode, a utilization circuit connected to said output electrode, a circuit for directly connecting 30 the output electrode of said first-named discharge device to one of said control electrodes, and a circuit including a series resistance and reactance connecting the output electrode of said first named device to another of said control 35 electrodes, whereby said second electron discharge device is controlled in accordance with the variations in light intensity and the rate of change of said variations.

4. In a facsimile transmitting system, the 40 method of controlling a thermionic tube having a plurality of control electrodes in accordance with messages comprising contrasting markings

on a background which includes the steps of impressing on one of said control electrodes potential variations in accordance with the contrast of the message, and impressing on another of said control electrodes potential variations 5 characteristic of the rate of change in contrast between various portions of said message.

5. The method of enhancing the definition of a facsimile message comprising contrasting markings on a background which comprises the 10 steps of producing pulsating currents the intensity of which is characteristic of the contrast of said markings and background, producing a potential the amplitude of which varies in direct proportion to the pulsating currents, producing 15 a second potential the amplitude of which varies in accordance with the rate of change of the pulsating currents, and simultaneously utilizing both of the produced potentials to produce a single current variation. 20

6. The method of increasing the definition of facsimile messages comprising dark and light contrasting markings which includes the steps of producing a potential variation characteristic of the contrast of the markings, producing a 25 second potential variation characteristic of the rate of change of the first produced potential variation, and individually utilizing the produced potentials to control a single electron stream.

7. The method of increasing the variations of 30 signal modulations on a carrier wave characteristic of contrasting graphic markings which includes the steps of producing light variations characteristic of said contrasting markings, producing current variations in accordance with the 35 light variations, producing potential variations characteristic of the rate of change of said light variations, combining the produced potential and current variations to produce a single signal series, and impressing the signal series on a carrier wave. 40

CLARENCE W. HANSELL.
